UNITED STATES PATENT OFFICE.

NEIL E. SALSICH, OF BETHLEHEM, PENNSYLVANIA.

SWITCH STAND.

Application filed December 4, 1924. Serial No. 753,784.

To all whom it may concern:

Be it known that I, NEIL E. SALSICH, a citizen of the United States, and residing at Bethlehem, Lehigh County, State of Pennsylvania, have invented certain new and useful Improvements in Switch Stands, of which the following is a specification.

My invention relates to switches, and more particularly to those of the parallel-throw, positive, dead-center type, and it has for an object to provide a switch stand of this character which shall be strong, which shall have the latching devices for the actuating lever thereof constituted as integral parts of the stand, and which shall present relatively greater bearing area for contact with ties than has heretofore been customary.

Switch stands of the general type to which my improvement is applicable have heretofore included a base member which is of substantially uniform width from end to end, terminal portions of the base member being spiked to adjacent ties and the intermediate portion constituting a part of the housing structure for the switch mechanism. With switch stands of this type, wherein the actuating shaft or spindle extends laterally or horizontally and a lever is attached to such shaft or spindle, it has been customary practice to provide separate latching devices which are spiked to the ties to hold the lever in its positions. In accordance with my invention, I widen the terminal or foot portions of the base member to such an extent that such portions extend laterally of the switch stand beyond the outer end of the bearing for the actuating shaft or spindle so that the latching device may be a part of the base member casting. Accordingly, therefore, it is an object of my invention to provide a base member for a switch of the type having a lever movable in a substantially vertical plane which is sufficiently wide at its ends to provide for integral latching devices for the lever.

Apparatus made in accordance with my invention is illustrated in the accompanying drawings, forming a part of this application, in which:

Fig. 1 is an elevational view of a switch stand incorporating my improved type of base member;

Fig. 2 is a plan view of my improved base member;

Fig. 3 is a side elevation of the structure shown in Fig. 2; and,

Fig. 4 is an end elevation of the structure shown in Fig. 2.

Referring now to the drawings for a better understanding of my invention, I show a switch stand including a base member 10 and a cover 11 adapted to be secured thereto by bolts 12. The cover has secured to the top thereof a sleeve member 13 for the target shaft 14, the latter carrying, at its upper end, a target 15. The cover and the base member have mating portions 16 and 17 which extend laterally thereof and define a bearing for the actuating shaft or spindle 18, to which is secured an actuating lever 19. The structure so far described is old and well known in the art; and, as my invention is concerned with certain novel features of the base member 10, further description of the switch stand in general is unnecessary.

My improved base member 10 is comprised of a single casting which is widened sufficiently midway of its length to define a part of the housing, at 20, and the mating part 17 of the bearing for the actuating shaft or spindle 18. The housing, at 20, is comprised of the base member and a wall 25 which extends upwardly therefrom so that the bearing parts 17 are arranged above the upper surface of the base member. In order to distribute the material of the base member to the best advantage, it will be seen that the foot plates 21 are provided with boundary ribs 21' which greatly strengthen the base member, particularly in a transverse direction. The end portions 21 of the base member are made sufficiently wide so that they extend laterally of the bearing for the actuating shaft or spindle in order that latching devices, at 22, may be cast integrally with the base member.

In other words, I have devised a base member which is substantially U-shaped, the legs of which extend a sufficient distance laterally of the switch construction to provide integral latching devices 22 for the actuating lever 19.

The relatively wide terminal portions 21 of the base member constitute feet for the switch stand and the greater width over customary practice provides for increased bearing area on the ties with consequent less wear of the latter. Furthermore, since the spike openings 23 may be spaced further

apart widthwise of the stand, the spikes operate more effectively in holding the switch stand in place. Also, if the stationary parts of the latching devices 22 are cast integrally with the base member, separate installation and maintenance of the latching devices is unnecessary and it is at all times assured that the latching devices shall register with the path of movement of the 10 actuating lever.

From the foregoing, it will be apparent that my improved type of base member construction is advantageous for the following reasons: It provides a stronger supporting 15 structure for the stand with the result that, even though the target shaft and the surrounding sleeve extending upwardly from the cover should be bent over or broken, the stand possesses sufficient strength to permit 20 of the deformation or breakage of these parts without permitting of the upsetting of the stand or the breakage of the principal parts thereof, with the result that the stand may remain intact and hold switch points 25 in a set position even though the superstructure of the stand should be wrecked or demolished. Since the terminal or foot portions of the base member are made relatively-wide, the effective bearing area of the stand 30 on adjacent railway ties is greatly increased with the result that spikes may hold the base member in position more effectively and wear on the ties is diminished. The outstanding advantage of my improved base 35 member construction is, however, that the latching devices may be cast integrally with the terminal portions, thereby facilitating installation of the stand and assuring at all times that the latching devices shall be 40 aligned with the operating lever. A further advantage of this integral construction of the base member and latching devices is that a less number of spikes is required for all 45 of the switch parts and separate installation and maintenance of the latching devices is unnecessary.

While I have shown my invention in but one form, it will be obvious to those skilled in the art that it is not so limited, but is 50 susceptible of various other changes and modifications without departing from the spirit thereof, and I desire, therefore, that only such limitations shall be placed thereupon as are imposed by the prior art or as 55 are specifically set forth in the appended claims.

Having thus described the invention what I claim as new and desire to secure by Letters Patent is:

60 1. In a switch stand, the combination of a base member having an intermediate lower housing portion defined by the base member and by an upwardly extending wall integral therewith and having foot plate portions 65 adapted to rest on adjacent ties, a

lower bearing member carried by one side of the wall and spaced above the upper surface of the base member, an upper housing portion secured to the wall, an upper bearing member carried by the upper housing portion and mating with the lower bearing member, an actuating shaft fitting the bearing members, a lever connected to the shaft, said foot plates extending laterally beyond the outer ends of the bearing members and having spike-receiving openings adjacent to the ends thereof, integral latch posts carried by the lever side ends of the foot plates, and lever latching means carried by the latch posts. 70 75 80

2. In a switch stand, the combination of a base member having an intermediate lower housing portion defined by the base member and by an upwardly extending wall integral therewith and having foot plate portions 85 adapted to rest on adjacent ties, said foot plate portions having upwardly extending boundary ribs, a lower bearing member carried by one side of the wall and spaced above the upper surface of the base member, an upper housing portion secured to the wall, and an upper bearing member carried by the upper housing portion and mating with the lower bearing member, said bearing members forming a bearing for an actuating 90 95 shaft and said foot plates extending laterally beyond the outer end of the bearing and having spike-receiving openings adjacent to the ends thereof.

3. In a switch stand, the combination of a 100 base member having an intermediate lower housing portion defined by the base member and by an upwardly extending wall integral therewith and having terminal foot plate portions adapted to rest on adjacent 105 ties, a lower bearing member carried by one side of the wall and spaced above the upper surface of the base member, an upper housing portion secured to the wall, an upper bearing member carried by the upper 110 housing portion and mating with the lower bearing member, and superstructure including an upwardly extending sleeve carried by the upper housing portion, said bearing members forming a bearing for an actuating shaft and said foot plates extending laterally beyond the outer end of the bearing and each having spike-receiving openings including openings adjacent to the ends 115 thereof, whereby the switch stand may be 120 maintained in place with wreckage of its superstructure.

4. In a switch stand, the combination of a base member having an intermediate lower housing portion defined by the base member and by an upwardly extending wall integral therewith and having terminal foot plate portions adapted to rest on adjacent ties, a lower bearing member carried by one side of the wall and spaced above the up- 125 130

per surface of the base member, an upper housing portion secured to the wall, and an upper bearing member carried by the upper housing portion and mating with the lower bearing member, said bearing members cooperating to form a bearing for a switch actuating shaft and said foot plates

extending laterally beyond the outer end of the bearing and each having spike-receiving openings adjacent to the ends thereof. 10
In testimony whereof I hereunto affix my signature this 2nd day of December, 1924.

NEIL E. SALSICH.
